(57) **CLAIM**

The ornamental design for a recording medium, as shown and described.

DESCRIPTION

FIG. 1 is a perspective view of a recording medium, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an end view thereof, taken along the line 8-8 in FIG. 6;

FIG. 9 is an end view thereof, taken along the line 9-9 in FIG. 6;

FIG. 10 is an end view thereof, taken along the line 10-10 in FIG. 2; and,

FIG. 11 is a perspective view showing a state where a USB connector is slid out.

The broken lines in FIG. 2 are included to indicate the cutting plane of FIG. 10. The broken lines shown in FIGS. 8, 9 and 10 are for environmental purposes only and form no part of the claimed design.
